UNITED STATES PATENT OFFICE

2,478,539

SPIRAL SOUND RECORD STRIP

Richard G. Leitner, Los Angeles, Calif., assignor
to Frank Rieber, New York, N. Y.; Lu Garda
Rieber executrix of said Frank Rieber, deceased

Application January 18, 1943, Serial No. 472,792

4 Claims. (Cl. 274—43)

1

This invention relates to new and useful improvements in sound records.

One object of the invention comprises, inter alia, a sound record and coordinated means for the identification of groove sections on such sound record.

The invention broadly comprises first means defining a substantially plane surface, at least one spiral sound groove on said surface, and second means identifying sections of said sound groove arranged in sequence coordinated with the sequence of said groove sections, and preferably in a ratio of their linear sequence to groove section sequence in excess of 1:1, for registry with stylus position indicator means.

In its preferred form, the sound record in accordance with the invention carries the groove section identifying means thereon. I prefer to use a record, in accordance with the invention, in connection with sound translating devices in which such record is held in a substantially stationary position with the stylus head moving to track in the sound groove. It is thus possible to read matter printed or written on the record even while the same is being played. Such printed or written matter may embrace titles, lyrics and/or music, indices or any other desired legend. This legend or index material, preferably carried on the sound record itself and arranged in sequence coordinated with the sequence of the groove sections, identifies given points on or sections of the sound record. If such sound record is used in a device having a suitable position or progress indicator appropriately coordinated with the sound translating stylus of such device, the position or positioning of the indicator, in registry with a predetermined identifying index or legend mark, fixes the stylus position on the sound record at the point identified by such mark.

The advantages of my novel sound record are still further enhanced by the use of a so-called constant velocity groove, i. e., a groove in which any given frequency on any portion thereof is represented by the same number of undulations per unit length of groove. This combination of constant velocity sound groove and the index or legend marks or matter referred to makes it possible to produce a "talking book," i. e., a book or the like recorded in sound reproducible form. This desideratum is possible as the combination is productive of a cooperative relationship which permits a sound reproducible record to contain uniformly the largest possible amount of recorded material per available area capable of 55 pulse element.

2

detailed topic or the like identification from appropriate legend marks or matter for accurate stylus registry or observation of stylus progress by means of suitably stylus coordinated indicator means. The legend material in conjunction with a book recording may comprise, if desired, the entire book text or alternatively page or chapter identification matter.

Constant velocity sound grooves are obtained 10 by using a recording device or mechanism having a constant linear stylus velocity drive, i. e., a drive causing relative motion between the stylus and the record at constant linear groove velocity of said stylus and at varying angular velocity, 15 in compensation of length differentials between spirals of maximum and minimum diameter.

I find it of advantage to use a sound record 20 having at least two parallel straight sides and preferably a substantially rectangular or a square sound record. The use of such record, inter alia, facilitates its positioning as a stationary record element and provides a marginal portion on which the desired index matter or a portion thereof, or, the hereinafter mentioned signal means may be 25 carried. Furthermore, such record can be fed or guided more accurately into sound groove centered position on a sound translating device.

The invention of this record is primarily intended to be used with the apparatus shown in 30 my copending applications 460,267, now Patent Number 2,344,851, 460,264 and 460,265, all filed September 30, 1942. The invention will be more fully understood and will appear more clearly 35 from the following description in conjunction with the drawings in which:

Fig. 1 represents a top view of a sound translating device, such as is shown in my copending application and with which this novel record is intended to be used. Fig. 2 is a front view of the 40 structure shown in Fig. 1, giving a general idea of the nature of the apparatus.

Fig. 3 is a cross sectional view of a laminated record element with sections broken away;

Fig. 4 illustrates a top view of a record element 45 strip having a plurality of sound grooves;

Fig. 5 is part of a top view of a record element, with sections broken away, showing a braille index;

Fig. 6 is part of a top view of a record element, with sections broken away, showing signal slots;

Fig. 7 demonstrates a cross section of part of the record element shown in Fig. 6 illustrating signal slots, a registering light source and im-

Fig. 8 is a top view of a round form of record element in accordance with the invention; and

Fig. 9 illustrates a top view of a square form of record element in accordance with the invention.

Since the special features of the invention are particularly related to the apparatus, it will be helpful to give a brief description of the apparatus referring to Figs. 1 and 2.

A machine comprising primarily a casing 145, having horizontal slits in the opposite sides thereof near the top through which a continuous record strip 147 may be fed. This strip extends beneath a transparent cover 146 and above a vertically movable plate 152 having a central stud 154 to cooperate with openings 149 which are carried by the strip 147. This plate 152 is movable vertically into engagement with the movable sound tracks 148 positioned at various playing areas upon the strip after these latter have been moved into position in registry therewith, and this stud holds the playing area in registry with the rotating head 5, carrying a stylus carrier 7. Movement of this stylus carrier 7 radially over the record face is controlled by a cam follower 9 which engages a spiral groove on a plate 13, so that as the stylus carrier rotates it is compelled to move in a spiral conforming to the spiral sound track. The stylus carrier is moved vertically into engagement with the sound track as the plate 152 is raised into engagement with the sound strip.

A motor driven cone 70 is employed as a drive mechanism for rotating the stylus carrier and is so employed as to engage a disc 42 carried by head 5 to give to the stylus carrier a constant linear speed along the sound groove.

An indicator 144 is connected to the stylus to move in harmony with it and this indicator is movable over indicia 151 on the edge of the record strip so that the position of the indicator at any moment bears a predetermined relation to the position of the stylus in the sound track. This makes it possible to place an index of the contents of the sound track upon the record, such that the indicator will at all times point to the index when the stylus is in engagement with the corresponding part of the record.

At the close of playing of each individual sound track, the machine automatically lowers the plate 152 and raises follower 9 and the stylus, thus disengaging the record and permitting the record strip to be moved automatically to a new sound track.

As shown in the drawings (Figs. 8 and 9) the substantially flat surfaces 901 and 901' carry respectively the sound grooves 902 and 902' and legends 903 and 903'.

In its preferred form, as illustrated in Fig. 3, the record may be laminated, having a center strip of preferably non-transparent material, such as a paper strip 707, adapted to receive a suitable printed or written legend such as a table of contents, a visual index, or the like. Covering the center strip on each side and suitably secured or bonded thereto, is a thin layer of plastic material preferably relatively thin sheet material 708, carrying a sound reproduceable groove of either lateral or vertical cut type 721. This plastic material is preferably transparent and any suitable material adapted to receive a sound reproduceable groove of the type mentioned may be used, such as vinylite, cellulose acetate, ethyl cellulose and others of like character and nature. Consequently, one surface may serve as a protec-

tion for the printed visual index or legend, while the other surface carries sound impressions. A sound record of the type mentioned is preferably used in connection with a device in which the stylus plays the record from underneath. If desired, sound impressions may be carried on both surfaces and legend material may be printed on both sides of the center strip. Even in this case the visual legend material may extend to portions covered by the sheet material carrying sound grooves since the sound grooves do not obscure plainly printed or written matter.

As supplement to the visual index or other legend material, and particularly for use by the blind I may extend one edge of the record strip (Fig. 5) and provide thereon braille index marks 722. It is possible to provide (Figs. 6 and 7) suitable signal slots or marks 723 coordinated with given legend or index marks 724 and thus with given indicator coordinated stylus positions to actuate any desired mechanism. As for instance, illustrated in Fig. 7, the light source 725 secured to and moving with indicator 726 incites, when in registry with signal slots 723', the selenium or impulse element 727 thereby closing an electric circuit (not shown) to effect, for example, slide changing in a projection machine in a manner well known in the art.

Within the scope of my invention and as further embodiment thereof, I provide a strip of record element material as illustrated in Fig. 4. Such strip carries a multiple number of individual sound grooves, each provided with its own legend material. Such record strip, particularly when of the relatively thin laminated type, may be made sufficiently thin and flexible to be wound on a roll.

The use of the sound record, in accordance with my invention, and its operation, is illustrated by way of example in connection with a device of the type hereinafter illustrated, in which relative motion between the record and the sound translating stylus is achieved by rotation of the stylus, while the record is in a substantially stationary position.

Frame 145 serves as support for record material 147, which in the embodiment shown (Fig. 1) comprises a strip of successive individual sound records each having its individual spirally arranged sound groove 148, its individual centering aperture 149 and its center point indicator 150. Each individual portion may carry at the margin thereof, a suitable legend or index 151 with which the indicator point 144 may be brought into registry. Stylus positions relative given points on or sections of the record sound groove are coordinated with indicator positions in registry with identifying index marks. Stylus position or progress on the sound groove is thus ascertainable at any time from indicator position or progress on the index. Suitable arrangement for viewing the index should be made such as by way of a cover at least partly composed of transparent material.

Cover 146 cooperates with the frame and disc member 152 (Figs. 3 and 11) to properly support the record material. Frame 145 and cover 146 are so spaced as to permit the record material 147 to pass therebetween without the necessity of lifting the cover. Signal mark 153 (Fig. 1) is provided on the cover 146 to indicate centered position of record material when in registry with the center point mark 150.

Although a strip of successive units of record material has been illustrated in connection with the construction exemplified by way of preferred

embodiment in the drawings, it is possible to use individual pieces of record material and irrespective of their particular geometrical configuration. If substantially circular record material is used, a suitable modification of the frame may be necessary, within the skill of the artisan, to firmly hold the record material in place. I prefer, however, to use the square form of record material as the same offers many advantages not realized with other forms of record material.

The index or other legend indicator 144 is preferably so set that its zero mark corresponds to the outermost position of the sound translating stylus element. By turning control knob 124, the index indicator 144 may be set to any desired position between the outermost and innermost positions of the stylus element, i. e., to any given intermediate index point, predetermined for a particular sound groove relation, and the positioning of index 144 will automatically adjust the stylus of stylus element 7 to that position.

Though the device in the illustration herein used is exemplified as one operating from maximum to minimum radial position, it is of course understood that the same may be used by drive 20 directional reversal, such as by belt crossing in connection with record material in which the stylus element rotates in spirally outwardly extending engagement.

The foregoing description is for purposes of illustration and not of limitation, and the same is not to be limited except by the appended claims in which I have endeavored to claim broadly all inherent novelty.

I claim:

1. A record strip having spiral record areas at regularly spaced intervals, each record area being provided with a positioning opening, a spiral sound track and a set of indicating marks, each sound track and its corresponding set of indicating marks bearing the same relation to its positioning opening.

2. A device in accordance with claim 1 in which the indicating marks are transverse to the side of the strip.

3. A device in accordance with claim 1 having indicating marks transverse to the side of the strip, and a legend on the face of the strip opposite each sound track, showing a particular portion of the contents of the sound track of each area corresponding to the individual indicating mark corresponding to said area.

4. A device in accordance with claim 1 having indicating marks transverse to the side of the strip and a legend on the face of the strip opposite each sound track, showing a particular portion of the contents of the sound track of each corresponding to the individual indicating marks corresponding to said area, said sound track being of the constant linear velocity type.

RICHARD G. LEITNER.
